UNITED STATES PATENT OFFICE

157,734

BASE FOR ROLLER SKATES

Wayne S. Burton, Anderson, Ind.

Application December 26, 1947, Serial No. 143,353

Term of patent 3½ years

(Cl. D34—14)

To all whom it may concern:

Be it known that I, Wayne S. Burton, a citizen of the United States, residing at Anderson, in the county of Madison and State of Indiana, have invented a new, original, and ornamental Design for a Base for Roller Skates, of which the following is a specification, reference being had to the accompanying drawing, forming part thereof.

In the drawing:

Figure 1 is a perspective view of a base for roller skates, showing my new design,

Figure 2 is a top plan view,

Figure 3 is a side elevational view,

Figure 4 is a rear end elevational view, and

Figure 5 is a bottom plan view thereof.

I claim:

The ornamental design for a base for roller skates, as shown.

WAYNE S. BURTON.
